UNITED STATES PATENT OFFICE.

ERNEST A. SCHROEDER AND JOHN N. TOOKER, OF SYRACUSE, NEW YORK, ASSIGNEES
TO CHURCH & DWIGHT COMPANY, OF NEW YORK, N. Y., A CORPORATION OF MAINE.

CARTON-HANDLING MACHINE.

1,277,139.

Specification of Letters Patent. Patented Aug. 27, 1918.

Original application filed July 20, 1915, Serial No. 40,823. Divided and this application filed February 26, 1916. Serial No. 80,655.

To all whom it may concern:

Be it known that we, ERNEST A. SCHROEDER and JOHN N. TOOKER, citizens of the United States, and residents of Syracuse, in the county of Onondaga and State of New York, have invented a new and useful Improvement in Carton-Handling Machines, of which the following is a specification.

The object of this invention is to provide a machine having novel mechanisms for supplying collapsed cartons and for feeding the collapsed cartons one by one to a predetermined point for subsequent operations thereon.

The invention consists in certain improvements in the construction, form and arrangement of the several parts of a carton handling machine whereby the above object may be carried out in a simple, rapid and effective manner.

The invention more specifically comprises an endless carrier arranged to feed the collapsed cartons upwardly along a carton supply magazine into position to be fed into the machine, and means for feeding in the collapsed cartons.

A practical embodiment of this invention is represented in the accompanying drawings, in which—

Figure 1 is a top plan view of a carton handling machine embodying our invention,

Fig. 2 is a vertical central section taken from front to rear through the machine with the several parts in the positions which they assume when the carton feeding and opening mechanism is at the limit of its forward movement,

Fig. 3 is a continuation of Fig. 2 from the indicated broken line to the floor line,

Fig. 4 is a detail section showing the means for controlling the movement of the feeding mechanism for the collapsed cartons, and

Fig. 5 is a detail view corresponding to Fig. 2, with the parts in the positions which they assume when the carton feeding and opening mechanism is at the limit of its rearward movement.

The carton supply mechanism will be first described. A vertically arranged magazine 17 is provided for the collapsed cartons. An endless carrier is provided for moving the

stack of collapsed cartons upwardly along the magazine 17 to bring the uppermost carton into position to be fed into the machine, which endless carrier comprises side chains 18 passing around upper and lower sprockets 19, 20, on cross shafts 21, 22, which chains are provided with shelves 23 arranged to be brought into their supporting position while passing upwardly along the supply magazine 17, by means of studs or rollers 24, arranged to travel along a vertically arranged cam 25. An intermittent movement is provided for the endless carrier by means of a ratchet wheel 26 engaged by a pawl 27 on a bar 28 provided with an eccentric connection 29 with the auxiliary drive shaft 14; the shaft 30 of the ratchet wheel 26 being connected to the upper shaft 21 of the endless carrier through a chain and sprocket connection 31, 32.

The pawl 27 is rendered inoperative when the stack of collapsed cartons reaches the predetermined height with reference to the feeding-in table 34 by the following device: The pawl 27 is provided with a bracket 35 which is connected to a rock arm 36 by a rod 37, which rock arm 36 is fixed to a rock shaft 38 mounted in suitable bearings on the machine frame. This rock shaft 38 has fast thereon a rock lever 39 having a carton engaging device comprising a cross bar 40 and depending arms 41 arranged to engage the top of the stack of collapsed cartons. A spring 42 and stop pin 43 yieldingly hold the depending arms 41 at the limit of their downward movement. This rock lever 39 is also provided with a roller 44 arranged to engage the upper combined feeding-in and opening-up suction nozzle, to lift the arms 41 from their engagement with the top of the stack of collapsed cartons when the said nozzle is at the limit of its forward movement, as will hereinafter more fully appear.

The suction means for feeding in and opening up the collapsed cartons is constructed, arranged and operated as follows: The upper suction nozzle 45 is provided with a feeding-in mouth 46 at its front end and a carton opening-up mouth 47 at its rear end, said mouths opening through the bottom 48 of the nozzle. The upper nozzle is also provided with a downwardly and

forwardly inclined top 49 arranged to engage the roller 44 on the rock lever 39. This upper nozzle 45 has a carriage 50 which reciprocates horizontally in a right line in 5 guides 51 in the side frames of the machine. This upper nozzle is connected through a flexible pipe 52 to any suitable air exhausting means, not shown herein.

The lower nozzle 53 has an opening-up 10 mouth 54 arranged to coact with the opening-up mouth 47 of the upper nozzle 45. This lower nozzle has a vertically reciprocating movement in a carriage 55 which reciprocates horizontally in a right line parallel 15 with the carriage 50 in suitable guides 56. The nozzle 53 is provided with a cross pin 57 projecting through its side walls and through vertically elongated slots 58 in the carriage 55, which cross pin is provided with 20 rollers 59 traveling in cam grooves 60. These cam grooves 60 are horizontally arranged for a portion of their length from the rear toward the front and are then directed upwardly and forwardly to cause the 25 lower nozzle to approach and recede from the upper nozzle as the two nozzles approach and recede from the forward limits of their movements.

The reciprocatory movements of the upper 30 and lower nozzles are under the control of a rock lever 61 pivoted at 62 near the base of the machine, which rock lever is engaged by an eccentric cam 63 on the auxiliary drive shaft 14. A rod 64 is connected at 65 to the upper nozzle carriage 50 and at 66 to the upper end of the rock lever 61. A rod 67 is connected at 68 to the lower nozzle carriage 55 and at its rear end has a loose 35 sliding engagement in the arms 69, 70, of a bracket 71 pivoted at 72 to the lever 61.

A lost motion connection, between the lower nozzle carriage and the rock lever 61, is provided for as follows: A stop 73 is 40 fixed to the rod 67, which stop is provided with rear and front shoulders 74, 75, arranged in position to be engaged by an arm 76 depending from the rod 64 at the rear end thereof. This stop 73 is furthermore provided with rear and front shoulders 77, 78, arranged to engage the opposite faces of 45 the arm 70 of the bracket 71. This lost motion connection between the carriages of the upper and lower nozzles and the rock lever 61, operates to bring the mouths 47 and 54 of the upper and lower suction nozzles 50 opposite each other as they reach one-half of their rearward travel; the remainder of their rearward travel in this position being accomplished by the engagement of 55 the arm 76 with the rear shoulder 74 of the stop 73.

While the mouths 47, 54, of the upper and lower suction nozzles are coacting to open 60 up a carton, the mouth 46 of the upper nozzle will be feeding the next succeeding col-

lapsed carton from the stack rearwardly along the feed table 34 into a position immediately to the rear of a spring actuated catch having fingers 79 projecting upwardly through slots 80 in the feed table 34. 70

To compensate for the arcs through which the corners of the cartons pass while opening and traveling with the movements, the mouth 54 of the lower nozzle is permitted a slight rearward movement against the tension of a spring 81, which spring 81 will return the mouth 54 to its normal position in alinement with the lower nozzle. This mouth 54 is furthermore provided with a spring-actuated stop 82 along its rear edge, 75 80 which stop projects above the lower nozzle a sufficient distance to engage the rear lower edge of the carton to prevent the carton from overrunning the mouth of the lower nozzle. When the opened-up carton is removed from between the opening-up mouths of the upper and lower suction nozzles, the stop 82 will be forced below the upper plane of the lower nozzle but will immediately resume its operative position when the 85 carton has passed rearwardly beyond it. 90

The lower suction nozzle is connected to the exhaust pipe 52 through the pipe 83, it being understood that there is a constant suction exerted through the upper and lower 95 suction nozzles at all times.

The collapsed cartons are fed upwardly along the carton supply magazine 17 by the intermittent movement of the endless carrier. As the upper suction nozzle 45 reaches 100 the limit of its forward movement, its mouth 46 will engage the topmost carton by suction effect and the carton will be carried over the table 34 past the fingers 79 of the catch at the limit of the rearward movement 105 of the suction nozzle 45. The finger 79 engages the collapsed carton and holds it on the table 34 until the mouth 47 in turn engages it at the limit of the next forward movement. In the meantime, the suction mouths 47 and 54 of the upper and lower nozzles are caused to engage the upper and lower sides of the previously fed-in carton and move the same inwardly, and, at the same time, opens up the carton. 110 115

It will be also be understood that if the collapsed cartons are being fed too rapidly upwardly along their magazine 17, the feeding of the cartons will be temporarily stopped by the coaction of the topmost carton with the arms 41 of the releasing device. 120

It will also be seen that these arms 41 are raised from their position on the top of the stack of collapsed cartons, by the engagement of the upper suction nozzle with the roller 44 at the time the suction nozzle is engaging the uppermost collapsed carton for feeding the same into the machine. 125

The mechanisms shown and described but not claimed herein, form the subject matter 130

of our United States Letters Patent No. 1220566, dated March 27, 1917, of which this is a division.

What we claim is:—

- 5 1. In a machine of the character described, a collapsed carton supply magazine, an endless carrier for feeding the cartons upwardly along the magazine into their feeding-in position, feeding-in means for the cartons and means adapted to be engaged either by the carton stack or the feeding-in means for arresting the movement of the carrier.
- 10 2. In a machine of the character de-

scribed, a collapsed carton supply magazine, 15 an intermittently moving endless carrier for feeding the cartons upwardly along the magazine into their feeding-in position, feeding-in means for the cartons and means adapted to be engaged either by the carton 20 stack or the feeding-in means for arresting the movement of the carrier.

In testimony that we claim the foregoing as our invention, we have signed our names this 21st day of February, 1916.

ERNEST A. SCHROEDER.
JOHN N. TOOKER.
